UNITED STATES PATENT OFFICE.

CHARLES A. CHASE, OF CHICAGO, ILLINOIS.

ELECTRIC SIGN.

SPECIFICATION forming part of Letters Patent No. 626,667, dated June 13, 1899.

Application filed March 29, 1899. Serial No. 710,925. (No model.)

To all whom it may concern:

Be it known that I, CHARLES A. CHASE, a citizen of the United States, residing at Chicago, in the county of Cook and State of Illinois, have invented a certain new and useful Improvement in Electric Signs, of which the following is a specification.

My invention relates to electric signs, and has for its object to provide a new and improved sign of this description.

My invention is illustrated in the accompanying drawings, wherein—

Figure 1 is a face view of a sign embodying my invention, showing some of the letters in position. Fig. 2 is a back view of the sign shown in Fig. 1. Fig. 3 is a section on line 3 3, Fig. 1. Fig. 4 is a detail showing the manner of insulating the wires at the point where they pass through the base-board of the sign.

Like letters refer to like parts throughout the several figures.

In carrying out my invention I provide a series of letters each made up in any desired manner of a series of electric lamps connected in circuit, these letters being applied to a suitable base-board, so as to form a given name or design or advertisement. In many instances the letters or characters upon the sign-board are frequently changed, as in advertising plays in theatres and in setting up various advertisements in stores and other places. When such a scheme is contemplated, great difficulty is met in utilizing the same letters by variously placing them upon the same board to produce different names and different advertising matter. When the sign is permanent, this difficulty is not met, for the electrical wires and connections when once made remain unchanged.

One of the objects of my present invention is to provide an electric sign wherein the letters can be easily and quickly changed in position and arranged to produce different names and designs and at the same time permit the use of the same material without injuring or mutilating any of the parts.

In carrying out my invention I provide a suitable base-board A, which forms the background for the letters and upon which the letters are mounted in the desired relation to each other. This base-board is provided with a series of slots or open spaces B B, said slots

or open spaces being preferably inclined, so that no open spaces will be apparent to observers looking at the face of the board. By 55 inclining these slots I am still enabled to pass the necessary connections therethrough and at the same time get the appearance of a substantially continuous base-board. The letters may be of any suitable construction; but I 6c have in the present instance shown them of the construction set out in my prior application, Serial No. 676,849. The several electric lights making up any given letter are connected together by suitable conductors. These 65 conductors C C preferably pass out at the end of the letter. When the letter is placed in position on the base-board, these conductors are passed through the proper slot or opening to the back of the board. On the back of the 70 board are provided the main conductors D D, permanently attached in position and provided with suitable cut-outs E E, distributed at various intervals. The conductors C C from each letter after being passed through the board are passed along the back of said board and connected to the nearest cut-out, so as to be in circuit with the main conductors. I prefer to provide the conductors C C with 75 suitable insulators F at the point where they 80 pass through the slots in the base-board.

It will be seen that by this arrangement I can make up any given advertisement or reading material upon the same sign by changing and disposing the letters in any manner desired and that this change can be easily and quickly made without disturbing the main electrical connections and without in any manner mutilating or injuring the base-board or the letters, for all that is necessary is to 90 arrange the letters in the new position, fastening them to the face of the base-board, and then pass the wires C C through the nearest slot and connect them to the main circuit. The great utility of this construction in facilitating the reproduction of new signs and new advertising matter will be readily understood by those versed in the art. It is of course evident that any suitable electrical connections and systems may be used and 95 that the number and position of the slots or openings will depend upon the result desired.

I have not attempted to illustrate the many uses of this device and have simply shown

one construction by means of which my invention may be readily understood. I therefore do not limit myself to the form, construction, and arrangement of the parts herein 5 shown.

I claim—

1. An electric sign, comprising a base-board provided with one or more slots or open spaces, a series of electric lights attached to suitable 10 supports to form letters or characters, said letters or characters attached to the base-board in proper relation to each other, suitable connections extending from said electric lights through said slots or open spaces to 15 the back of the base-board and attached to conductors located on said back.

2. An electric sign, comprising a base-board provided with a series of slots or open spaces, a series of letters comprising electric lights 20 arranged to form the contour of the letter, said letters attached to the face of the board to form the desired sign, suitable electrical conductors attached to the back of the board, and suitable connections extending from the 25 said conductors through the slots or open spaces to the letters, substantially as described.

3. An electric sign adapted to permit the changing of the advertising matter thereon, comprising a base-board provided with a series of slots or open spaces, a series of letters made up of electric lights and attached to the face of the board in the desired relation to each other, an electric circuit attached to the back 35 of the board and provided at suitable intervals with devices by means of which the lamps in the letters may be connected in circuit, conductors leading from said letters through the slots to said devices, so as to connect the 40 letters in circuit, the slots arranged to permit the connections to be made when the position

of the letters on the board is varied without mutilating the parts.

4. An electric sign adapted to permit the changing of the advertising matter thereon, 45 comprising a base-board provided with a series of slots or open spaces, a series of letters made up of electric lights and attached to the face of the board in the desired relation to each other, an electric circuit attached to the back of the board and provided at suitable intervals with devices by means of which the lamps in the letters may be connected in circuit, conductors leading from said letters through the slots to said devices, so as to connect the letters in circuit, the slots arranged to permit the connections to be made when the position of the letters on the board is varied without mutilating the parts, said slots inclined with relation to the face of the board, 55 substantially as described.

5. An electric sign, comprising a base-board, a series of letters adapted to be attached to the face of said base-board in the proper relation to each other to produce the desired 65 effect, a series of electrical conductors extending across the back of the board and provided at intervals with suitable cut-outs, a series of slots or open spaces in said board, conductors connected with each of said letters, said conductors passing through the slots in the board and connected with one of said cut-outs, the cut-outs and slots so arranged that the connection can be easily and quickly made regardless of the position occupied by 70 the letter, whereby various signs or designs may be produced upon the same base-board without mutilating the parts.

CHARLES A. CHASE.
